(57) **CLAIM**

We claim the ornamental design for a sofa, as shown and described.

DESCRIPTION

FIG. 1 is a perspective view of a sofa showing a first embodiment of our new design.

FIG. 2 is a front view of the sofa of FIG. 1.

FIG. 3 is a rear view of the sofa of FIG. 1.

FIG. 4 is a first side view of the sofa of FIG. 1.

FIG. 5 is a second side view of the sofa of FIG. 1.

FIG. 6 is a top view of the sofa of FIG. 1.

FIG. 7 is a bottom view of the sofa of FIG. 1.

FIG. 8 is a perspective view of a portion of a sofa showing a second embodiment of our new design.

FIG. 9 is a front view of the portion of a sofa of FIG. 8.

FIG. 10 is a rear view of the portion of a sofa of FIG. 8.

FIG. 11 is a first side view of the portion of a sofa of FIG. 8.

FIG. 12 is a second side view of the portion of a sofa of FIG. 8.

FIG. 13 is a top view of the portion of a sofa of FIG. 8; and,

FIG. 14 is a bottom view of the portion of a sofa of FIG. 8. The broken lines in the figures are for the purpose of illustrating portions of the sofa, which form no part of the claimed design.
